UNITED STATES PATENT OFFICE.

WILLIAM M. SCHOLL, OF, CHICAGO, ILLINOIS.

INSTEP-ARCH SUPPORTER.

1,142,849.

Specification of Letters Patent. Patented June 15, 1915.

Application filed January 22, 1912. Serial No. 672,601.

To all whom it may concern:

Be it known that I, WILLIAM M. SCHOLL, a citizen of the United States, residing at Chicago, in the county of Cook and State of Illinois, have invented certain new and useful Improvements in Instep-Arch Supporters, of which the following is a specification.

My invention relates to improvements in instep supporters and has for its general objects to provide a construction which is adequately reinforced for great strength at the points where it is most liable to fracture, which is capable of ready adjustment as to height, and which has sufficient resiliency 15 for comfort and ease in use.

In the drawings, wherein I have illustrated an embodiment of my invention, Figure 1 is a bottom plan view; Fig. 2 is a transverse section on line 2—2 of Fig. 1; 20 and Fig. 3 is a longitudinal section on line 3—3 of Fig. 1.

In the drawing, 5 indicates in general a main metallic arch-plate adapted to underlie and generally to conform to the compound curvatures of the under side of the human instep arch, so as to afford adequate support to the foot arch, said plate 5 preferably having a wing extension 6 to underlie the inside surface of the instep arch, said 25 wing portion 6 preferably being laterally slit at a number of places, shown at 7, for resiliency and for ease of adjustment of the wing to the configuration of the particular foot to be fitted.

The arch plate preferably extends from adjacent the ball of the foot approximately to the heel thereof and transversely to underlie the entire plantar surface of the foot, its transverse extent at both its front and 30 rear ends being sufficient to give adequate bearing in the shoe. The arching of the plate elevates its central portion considerably, as indicated in Figs. 2 and 3, both transversely and longitudinally, so that 35 above the bearing plane of the ends of the plate is left ample space for the reinforcing structure to be described.

Along the under side of the plate near the transverse mid-portion thereof, I provide a longitudinally extending metal truss 9, preferably formed integrally with the plate. To this end I preferably slit the plate longitudinally on two parallel lines to free a lengthwise strip of metal, and thereafter I depress 50 the metal strip as illustrated. The metal truss member 9 preferably merges at both

ends into the body of the plate, and between such ends is forced down so that its mid portion is below the level of the lower surface of the plate at about the highest point 55 of the longitudinal arch of the plate. For strengthening the truss member a central portion of the metal truss-strip is preferably cupped transversely, as shown at 10 in Fig. 2, the upturned side edges of the 60 cupped portions merging into the depressed central portion of the truss adjacent the ends thereof.

Between the depressed central portion of the truss 9 and the under side of the plate 5, 70 I interpose a transverse supplemental plate 11, providing a tongue portion 12 and an anchorage base 13. The tongue 12 passes over the truss 9, under the plane of the plate 5, to bridge transversely the truss-slot; and the base 13, elongated preferably to extend longitudinally beyond the area of the slits 7 75 and beyond the length of the truss 9, is riveted as at 14—14 to the main plate near the extremities of its longitudinal extent. 80

The structure thus far described in itself forms a strong and efficient arch, but as a convenient aid in making the arch comfortably resilient I preferably interpose a resilient cushion member, such as a block of 85 rubber 16, between the transverse auxiliary plate 13 and the truss member 9.

Along substantially the entire extent of its outer edge, the main plate is preferably down-turned as at 17 for reinforcement and 90 strength, and to make a neat fit with the shoe insole.

In customary fashion, the metal arch plate 5 is preferably overlain by a cover piece of leather indicated at 18, the edges thereof being skived to interfit with the contiguous parts of the shoe. 95

It will be seen that the striking out of the central portion of the plate into a truss enables an easy adjustment of the height of 100 the plate above the truss to be effected; that the interposition of various sizes of rubber blocks 16, or other more or less resilient strut-members, between the auxiliary plate 13 and the truss 9 tends to fix the adjustment 105 at the desired point, while allowing sufficient resiliency to make the device yield somewhat under the imposed weight of the wearer; that the longitudinal extension of the auxiliary plate beyond the areas of the 110 main plate to which the longitudinal and transverse slits are localized gives effective

reinforcement for the plate to prevent its breakage in the area affected by the slits, and that the strength imparted by the truss formation gives it capability of carrying 5 heavy weight without more than the desirable yielding incident to the resiliency of the rubber body preferably interposed between the truss and the plate.

While I have herein described in some detail a specific embodiment of my invention, it will be apparent to those skilled in the art that numerous changes in the details thereof might be made without departing from the spirit of my invention and within 15 the scope of the appended claims.

What I claim is:

1. In a device of the character described, the combination of a main plate, a truss member integral with the main plate, 20 formed by depressing a portion thereof below the general level of the main plate, and an auxiliary plate extending between said main plate and the truss member, spanning the opening in the main plate and bearing 25 against said main plate laterally beyond the edges of the opening and at one side longitudinally beyond the ends of the truss member.

2. In a device of the character described, 30 the combination of a leather cover piece, a main plate shaped to conform to the under side of the human foot and having a lateral extension provided with suitable slits to weaken said portion of the plate for increased resiliency, a truss below the central portion of the plate extending lengthwise thereof and at its center spaced apart below the general level of the under side of the plate, and a transverse reinforcing plate secured 35 to the main plate having a portion extending between the truss and the body of the plate and a longitudinally extending portion, laterally terminating between the center line and slitted portion of the main 40 plate and longitudinally extending beyond the slitted portion of the main plate.

3. In a device of the character described, 45 a main plate having a slitted side extension,

a relatively narrow truss member located adjacent the transverse center of said plate, 50 extending, below the level of the under surface of the plate, lengthwise of the plate over substantially the same longitudinal distance as the slits in the side extension, and an auxiliary plate extending between said 55 main plate and the truss member, and having its side edge terminating between the truss and the slitted extension part of the main plate.

4. In a device of the character described, 60 the combination of a main plate having a slitted side extension and a truss member extending lengthwise of the plate near the middle thereof over substantially the same longitudinal distance as the slitted portion 65 of the extension, and an auxiliary plate secured to the main plate at points longitudinally beyond the slitted portion of the main plate.

5. In a device of the character described, 70 the combination of a main plate having a slitted side extension and a truss member extending lengthwise near the middle of the plate over substantially the same longitudinal distance as the slitted portion of the 75 extension, and an auxiliary plate secured to the main plate at points longitudinally beyond the slitted portion, said auxiliary plate extending between the truss member and the plate.

6. In a device of the character described, the combination of a main plate, a truss member formed integral therewith by striking down a portion of the main plate, a transverse plate underlying and secured to 85 the main plate extending through the space between the truss and body of the main plate, and a resilient member interposed between the truss member and the auxiliary plate.

In testimony whereof I hereunto set my hand in the presence of two witnesses.

WILLIAM M. SCHOLL.

In the presence of—

W. LINN ALLEN,

MARY F. ALLEN.
